UNITED STATES PATENT OFFICE

2,438,398

PREPARATION OF CYCLOPENTADIENE

Robert M. Kennedy, Drexel Hill, Pa., assignor to
Sun Oil Company, Philadelphia, Pa., a corpora-
tion of New Jersey

No Drawing. Application August 19, 1947,
Serial No. 769,521

3 Claims. (Cl. 260—666)

1

This invention relates to dehydrogenation and cyclization of hydrocarbons. Specifically it relates to the dehydrogenation and cyclization of n-pentane, 1-pentene, 2-pentene and 1,3 pentadiene to 1,3 cyclopentadiene. More specifically the invention is concerned with a commercially feasible process for the conversion of n-pentane to 1,3 cyclopentadiene by converting the saturated material to 1,3 pentadiene and cyclizing the 1,3 pentadiene to 1,3 cyclopentadiene.

The conversion of pentane to 1,3 cyclopentadiene is considered to take place by way of, say, 1-pentene and 1,3 pentadiene. The yield of 1,3 cyclopentadiene will be higher when the charging stock requires the least amount of dehydrogenation. Accordingly, the invention will be described with reference to the conversion of 1,3 pentadiene to 1,3 cyclopentadiene to which it is pre-eminently suited. The reactions of the foregoing enumerated steps can be represented as follows:

According to the invention, 1,3 pentadiene, admixed with n-pentane and/or n-pentenes, or other gases, is subjected to a dehydrogenating temperature for a time sufficient to effect a desired extent of conversion to 1,3 cyclopentadiene. Thus, it will be seen that it has been discovered that a five carbon straight chain hydrocarbon can be dehydrogenated and cyclized thermally to form 1,3 cyclopentadiene. According to the invention, contact masses suited to the uniform

2

and efficient heating of the charge stock can be employed. Suitable contact masses which can be employed are described and claimed in the following copending applications for patent filed by the present inventor together with Stanford J. Hetzel: Serial No. 630,691, filed November 24, 1945, now Patent 2,438,399; Serial No. 630,692, filed November 24, 1945, now Patent 2,438,400; Serial No. 636,270, filed December 20, 1945, and Serial No. 650,394, filed February 26, 1946, now Patent 2,438,401 and are "silica gel," "chromia on alumina," "activated alumina," and "silicon carbide," respectively.

The temperature employed for the dehydrogenation of the hydrocarbons, in the instant case 1,3 pentadiene, will vary depending upon the other conditions of operation, on the nature or purity of the charging stock and on the contact mass, if any, employed. The conversion of 1,3 pentadiene can be advantageously effected at a temperature within the range 300° C. to a temperature beyond which excessive decomposition of the hydrocarbons will take place. More specifically a temperature within the range 400° C.—700° C., preferably 450° C.—650° C., can be employed.

While the conversion per pass is substantially independent of pressure it has been found that lower pressures seem to form higher yields on recycling. Accordingly, while higher and lower pressures are not excluded from the scope of the invention, pressures in the range of 1000 mm. Hg—10 mm. Hg absolute, preferably 200 mm. Hg—10 mm. Hg, can be employed.

The time during which the 1,3 pentadiene is subjected to a dehydrogenating temperature is a factor to be considered. There appears to be an optimum range of time, that is, 0.06 second to 60 seconds. When a contact mass has been employed the optimum range of contact time has been found to correspond to charging rates of 0.25 gram/minute/100 grams—10 grams/minute/100 grams of contact mass. However, higher and lower charging rates are not excluded from the scope of the invention.

The following examples illustrate the invention:

Example 1

1,3 pentadiene of approximately 88% pentadiene content was fed to a reaction tube consisting of a length of ordinary carbon steel pipe approximately one inch inside diameter and having a volume of 128 cc. The pipe was maintained at 600° C. by external heating means and the sys-

tem was evacuated in a controlled manner such that while the liquid pentadiene was being fed into it, the pressure remained at 30 mm. Hg absolute pressure. Means were provided for vaporizing the 1,3 pentadiene before it entered the reaction tube and preheating it to approximately 550° C. The rate of feed was maintained constant to provide a residence time in the zone at 600° C. of about 2.4 seconds. The products were condensed and analysis for cyclopentadiene showed a once-through yield of 7.3%. Other products (gas, polymer, etc.) were obtained to an extent such that by recycling the unreacted 1,3 pentadiene an ultimate yield of approximately 42% cyclopentadiene would be obtained.

Example 2

With the same apparatus and technique as in Example 1, the same charge of 1,3 pentadiene was cyclized at 615° C., 15 mm. Hg and a residence time of 0.78 second. A once-through yield of 3.8% cyclopentadiene was obtained with a calculated ultimate yield of 30.4%.

It will be apparent to those versed in the art that modification and variation are possible within the scope of the invention as defined in the appended claims, the essence of the invention being that n-pentane, 1-pentene, 2-pentene and/or 1,3 pentadiene can be dehydrogenated and cyclized to 1,3 cyclopentadiene by subjecting these compounds to a dehydrogenation temperature. That

any five carbon straight chain hydrocarbon could be cyclized by subjecting it to a dehydrogenation temperature was not predictable.

I claim:

- 5 1. A process for the dehydrogenation and cyclization of 1,3 pentadiene to 1,3 cyclopentadiene which comprises subjecting said 1,3 pentadiene to dehydrogenation at a temperature within the range of 300° C. to 700° C. for a time sufficient to effect a desired extent of dehydrogenation and cyclization.
- 10 2. A process for the dehydrogenation and cyclization of 1,3 pentadiene to 1,3 cyclopentadiene which comprises subjecting said 1,3 pentadiene to dehydrogenation at a temperature within the range of 400° C.-700° C. for a time sufficient to effect a desired extent of dehydrogenation and cyclization.
- 15 3. A process according to claim 2 wherein the pressure is within the range of 1000 mm. Hg to 10 mm. Hg.

ROBERT M. KENNEDY.
